UNITED STATES PATENT OFFICE.

VERNON H. MEYER, OF CLEVELAND, OHIO.

HYDROMETER.

1,391,000.

Specification of Letters Patent. Patented Sept. 20, 1921.

Application filed November 29, 1920. Serial No. 427,072.

To all whom it may concern:

Be it known that I, VERNON H. MEYER, a citizen of the United States, residing at Cleveland, in the county of Cuyahoga and State of Ohio, have invented certain new and useful Improvements in Hydrometers, of which the following is a specification.

This invention relates to hydrometers, and is particularly useful in connection with hydrometers of the type used for testing storage batteries. Ordinary hydrometers have the objection that they are liable to become broken if dropped, and furthermore the float breaks by contact with the barrel in handling the instrument. Some hydrometers have been provided in which the lower part of the barrel is made from solid rubber, but these have the objection that the lower end of the float cannot be seen, and so it is often not known whether the float has lifted or whether it is still resting on the bottom of the barrel.

The object of the present invention is to provide a hydrometer having means to prevent breakage thereof, either of the barrel or the float, and also to prevent the hydrometer rolling around on a smooth surface.

One of the principal features of the invention is a rubber liner which is placed in the lower part of the barrel and which prevents contact between the float and the glass wall of the barrel.

A further feature of the invention is the provision of a cap or band at the top of the float, which will prevent contact of the upper end thereof with the wall of the barrel.

A further feature of the invention is the position of means to prevent the float from entering the compressible bulb at the top of the barrel, which sometimes results in breakage of the float when the bulb is grasped.

By these and other means to be described the float is practically protected in all positions and it is almost impossible to accidentally break either the float or the barrel of the instrument, and at the same time the barrel is free from the objections incident to making it in two sections, which often results in leakage at the joint.

The invention is illustrated in the accompanying drawings in which Figure 1 is a longitudinal section of the hydrometer. Fig. 2 is a section on the line 2—2 of Fig. 1. Fig. 3 is a plan of the rubber liner.

Referring specifically to the drawings, 6 indicates the glass barrel of a hydrometer provided at its upper end with a compressible bulb 7 and at its lower end with a tube 8, as usual. The bulb is protected exteriorly 60 by angular shields 9 and 10, made of rubber, one of which fits on the neck 11 at the lower end of the barrel and the other on the neck 12 at the top thereof. These shields are of sufficient size to hold the barrel out of contact 65 with the surface on which the instrument is laid, and will also prevent contact of the barrel with a surface on which the instrument may be accidentally dropped. These shields therefore prevent much of the breakage incident to accidental dropping of the instrument. A glass float 13 is contained in the barrel as usual. The lower part of this float is prevented from contact with the glass wall of the barrel by means of a circular liner 14, consisting of a perforated sheet 70 of rubber which is rolled to a cylindrical form and inserted in the lower part of the barrel. The openings 15 in the liner are for the purpose of permitting inspection of the 80 float, so that it can be seen when the same is actually floating. A plug 16 of rubber is also fitted in the lower end of the barrel, so that the float cannot strike the bottom there- 75 of when the liquid is discharged from the 85 barrel.

At its upper end the float is provided with a ring or cap 17 of rubber which also prevents contact of that end of the float with the upper part of the barrel. And furthermore a plug 18 of rubber is fitted in the neck 12 at the top of the barrel and so prevents the float rising into the bulb 7 or dropping thereinto if the hydrometer should be inverted. This plug 18 has holes 19 to enable 95 the bulb 7 to perform its function.

The float is thus practically surrounded by rubber protectors, in consequence of which there is little possibility of the float being broken by shock or by contact of the barrel of 100 the instrument, and the barrel is also exteriorly protected by the means above described. These advantages will be appreciated by persons using such instruments, who are aware of the objections incident to frequent 105 breakage of the parts.

I claim:

1. The combination with a hydrometer barrel, bulb and float, of a cushion liner in the barrel, extending sufficiently above the 110

bottom of the barrel to prevent contact of the float with any part of the wall of the barrel.

2. The combination with a hydrometer barrel, bulb and float, of a cushion liner in the barrel, of sufficient extent to obscure a portion of the float and to prevent contact of the float with the wall of the barrel, said liner having holes through the same through which the position of the float may be seen.
5. The combination with a hydrometer barrel and float, of a liner in the lower part
- 10.

of the barrel, of sufficient extent to obscure a portion of the float and to prevent contact of the float with the wall of the barrel, said liner consisting of a perforated sheet of rubber inserted within the barrel.

In testimony whereof, I affix my signature in presence of two witnesses.

VERNON H. MEYER.
